CLAIM

The ornamental design for a combined thermometer and casing, as shown and described.

DESCRIPTION

FIG. 1 is a front elevational view of a combined thermometer and casing showing my new design, the thermometer and the casing being in their assembled condition;

FIG. 2 is a left-side elevational view thereof, the right side elevational view being a mirror image;

FIG. 3 is a rear elevational view thereof;

FIG. 4 is a top plan view thereof;

FIG. 5 is a bottom plan view thereof;

FIG. 6 is a front elevational view of the thermometer removed from the casing for ease of illustration;

FIG. 7 is a left-side elevational view of FIG. 6, the right side elevational view being identical;

FIG. 8 is a rear elevational view of FIG. 6;

FIG. 9 is a top plan view of FIG. 6;

FIG. 10 is a bottom plan view of FIG. 6;

FIG. 11 is a front elevational view of the casing, with the thermometer removed for ease of illustration.

FIG. 12 is a left side elevational view of FIG. 11, the right side elevational view being a mirror image;

FIG. 13 is a rear elevational view of FIG. 11;

FIG. 14 is a top plan view of FIG. 11; and

FIG. 15 is a bottom plan view of FIG. 11.

FIG.1 FIG.2 FIG.3 FIG.4 FIG.5 FIG.6 FIG.7 FIG.8 FIG.9 FIG.10 FIG.12 FIG.13 FIG.14 FIG.15 FIG.16
